UNITED STATES PATENT OFFICE.

WILLIAM B. POTTER, OF SCHENECTADY, NEW YORK, ASSIGNOR TO GENERAL ELECTRIC COMPANY, A CORPORATION OF NEW YORK.

ELECTRIC RAILWAY.

SPECIFICATION forming part of Letters Patent No. 697,013, dated April 8, 1902.

Application filed December 20, 1900. Serial No. 40,468. (No model.)

To all whom it may concern:

Be it known that I, WILLIAM B. POTTER, a citizen of the United States, residing at Schenectady, county of Schenectady, State of New York, have invented certain new and useful Improvements in Electric Railways, (Case No. 1,637,) of which the following is a specification.

This matter relates to roadway structures for electric railways of the type provided with sectional service-supply conductors, which are in the form of contact buttons or studs rather than the ordinary rails employed in third-rail systems. While sectional third-rail systems are best adapted for extra urban or elevated railways on which cars are run in trains, the stud system is best adapted for city use, where the relatively short cars used will in their progress cover the successively-energized studs, so that no live contacts will be exposed in front of or behind a car. The problem presented is to provide such a structure that the studs will always be held in good contact with the leads, so that they will not fail to be energized successively as the car progresses, in spite of the rough usage to which they are subjected by the impact and sliding engagement of the collectors carried by the cars and from heavy city trucking. At the same time the structure must be such that the studs can be readily removed and replaced when they are worn down by the frictional engagement of the car-collectors or when it is desired to inspect the connections, and, furthermore, the conducting parts must be well insulated from the surrounding roadway.

I have conceived the idea of forming a conducting-stud of a separate metal piece which is independent of the rest of the structure, and I have discovered that the most advantageous manner of constructing a stud so that it may be securely held in position, but at the same time can be readily removed, is to make the stud of smaller diameter than the support which holds it and to pour molten soft metal in the space which separates the stud from the sides of the support, whereby the use of bolts or screws and like similar mechanical means which would become loosened in service and would also increase the

difficulty of removing the stud is obviated. Certain other features of the construction herein disclosed can be used independently of that just described.

Figure 1 is an elevation of a structure embodying the invention. Fig. 2 is a plan view of the same. Fig. 3 is a vertical central section thereof, taken along the line of the direction of motion of the cars.

A casing C is provided with bolt-holes R, by which it can be suitably mounted in the roadway, as on the ties or sleepers. This casing C serves to retain a block of insulating material I, which is preferably of material such as asphalt, although other suitable insulating material, such as wood, may be used in cases when the structure is not exposed to destructive influences. This block of insulating material I has mounted in substantially its central upper part a conducting-support S of suitable material, such as cast-iron. This metal support S is perforated, as shown at O', and a lead L, suitably connected to the supply system, extends up through perforations O in the casing C and the block I, its end being held in electrical contact with the metal support S by the following means: The end of the lead L is suitably secured, as by soldering, to a terminal N, which is provided with a screw-threaded upward extension E. The terminal N engages with a lower shoulder D of the perforation O' in the support S, and a nut B engages the screw-threaded extension E of the terminal N and an upper shoulder U of the perforation O', so as to draw the terminal N into intimate contact with said support. The structure so far described is sunk in the roadway, so that the tops of the block I and the projecting walls S' of the support S are substantially flush with the level of the roadway.

The metal button A, which is mounted in the top of the metal support S in good electrical contact therewith, is constructed as follows: It is cast substantially as a disk of smaller diameter than the distance between the walls S' of the support, and its upper or wearing surface is preferably curved from the central portion to the periphery. At two or more portions of the periphery it is provided with projections P of such length that

their outer portions fit the inside diameter between the walls S' of the support S. The stud so constructed is inserted in the depression of the support S, formed by the outwardly-projecting walls S', so that its periphery is substantially on a level with the edges of the walls. The projections P serve as a means for centering the stud in the depression, so that a uniform distance is maintained between the periphery of the stud and the inner circumference of the walls of the support, and the portion of the disk or stud extending above the support constitutes a contacting surface with which the collectors carried by the cars engage. A suitable soft metal—such as lead, as shown in X—is then poured into the annular space between the stud and the support and this metal fills the interstices of the metal parts, so that the stud is securely held in place, its lower surface being in good contact with the upper surface of the depression in the support S. The nut B is covered by the stud, so that the intimate contact between the terminal N and the support S is not disturbed by traffic; but when the stud is removed these connections are readily accessible without further disturbance of the structure. When the stud is subjected to blows from the car-collector or from the wheels of heavy trucks, the projections P, which engage the walls S' of the support, prevent the metal filling from being compressed, and hence prevent the stud from becoming loosened in its seat. It may be necessary in some instances to provide, as shown in Fig. 2, more than two projections P, especially where the traffic is heavy. When only two projections are used, they should be arranged in alignment with the direction of motion of the cars and the collectors carried thereby. Several studs embodying the above-described construction have been subjected to a severe test for several months on a city street and are in as good condition to-day, without re-pairs, as they were at the time of their location, the metal fillings yet retaining the studs tightly in place.

A most important feature of the above-described stud lies in the fact that although it cannot be loosened in its seat by car collectors or trucks it can be readily removed by a moderately-powerful upward pull. For this purpose the holes H are formed in the stud for the reception of crowbars or power-tongs. Thus the stud is readily removed from its seat when it is desirable to do so for any reason, such as to replace it with a new stud or to examine the conductor connection, which is uncovered by the removal of the stud.

The holes H are formed in the projections P, whereby greater leverage is obtained, the outer sides of the projections P serving to prevent the holes H from being filled with the metal when the latter is poured in the free annular space between the stud and the support S. When the worn stud is removed, the metal filling can be readily removed, as there

is no union with the parts, and it disintegrates upon the removal of the stud.

In installing the structure the lead is inserted through the hole O in the casing C, which latter is then secured in place. The lead is then inserted in the perforation O' in the block I and the nut B screwed upon the threaded portion of the terminal N. The block I is then placed in position in the casing C, after which the stud A is secured in the conducting-support S in the manner above described.

What I claim as new, and desire to secure by Letters Patent of the United States, is—

1. In a structure for surface-contact rail-ways, the combination with a conducting-sup-70 port having an upper depression, of an inde-75 pendent metal disk or stud, which is remov-85 ably mounted in the depression to make con- tact with the support.

2. The combination with a conducting-sup-90 port having upper projecting walls, of a metal95 stud of smaller diameter than the distance between the walls, which rests between the latter to make contact with the support, and a metal filling between the sides of the stud and the walls of the support, to hold the lat-95 ter in position.

3. The combination with a conducting-sup-100 port having upwardly-projecting walls, of a105 metal stud of smaller diameter than the dis- tance between the walls, which rests between the walls to make contact with the support, a metal filling between the sides of the stud 110 and the walls of the support, and projections from the stud which engage the walls of the support to protect the metal filling.

4. The combination with a conducting-sup-115 port having an upper depression, of a metal120 stud with a smaller diameter than the de- pression and mounted therein, and a metal filling between the sides of the stud and the walls of the depression, said stud being formed with holes whereby it can be removed from the depression.

5. A stud for surface-contact electric rail-ways, which consists of an independent metal125 disk provided with lifting-holes.

6. The combination with a conducting-sup-130 port formed with a depression in its upper135 surface, of a metal surface-contact disk re- movably mounted therein, the said disk be- ing provided with lifting-holes.

7. The combination with a conducting-sup-140 port formed with a depression in its upper145 surface, of a metal surface-contact disk re- movably mounted therein, the said disk be- ing provided with lifting-holes, and a metal filling for securing said disk in position.

8. The combination with a conducting-sup-150 port formed with a shallow depression sub-stantially rectangular in cross-section in its155 upper surface, of a metal surface-contact disk removably mounted therein, the said disk be- ing provided with lifting-holes, and a metal filling for securing said disk in position.

9. The combination with a conducting-sup-

port formed with an upper depression, of a metal stud of smaller diameter than the depression and mounted therein, a metal filling between the stud and the support, said stud being formed with projections which engage the walls of the depression to center the stud therein and to prevent strains on the filling when the stud is subjected to blows, said stud being also formed with holes whereby it can be lifted from the position in which it is held by the metal filling, said holes being formed in said projections whereby the metal filling will not flow into them.

10. A stud for surface-contact electric railways, which consists of an independent metal disk formed with lateral projections, lifting-holes being formed in said projections.

11. The combination with a metal support formed with an upper depression, of a metal stud mounted therein and which has a smaller diameter than that of the depression, and a metal filling between the stud and the walls of the depression, which fills the interstices of the metal parts and secures the stud in position.

12. The combination with a metal support, of a lead extending downwardly therefrom, and a metal surface-stud removably secured to the support by a metal filling.

13. The combination with a vertically-perforated metal support, of a lead extending through the perforation from below and secured to the support from above, and a metal stud removably mounted on the support and covering the end of the lead.

14. In combination, a vertically-perforated metal support having upper and lower shoulders in the walls of the perforation, a metal connection-piece having an upwardly-extending screw-threaded portion, a lead secured to the lower part of the connection-piece, a nut which engages the upper shoulder of the support and also the threaded portion of the connection-piece, to draw the lower part of the connection-piece into good contact with the lower shoulder of the metal support, and a metal stud removably mounted on the upper part of the metal support to make good contact therewith.

15. In a roadway structure for surface-contact railways, the combination with a conducting-support, of an independent disk or stud which is removably mounted within a depression in said conducting-support, and an electrical connection extending downwardly from said support.

16. In a roadway structure, the combination with a conducting member, of insulating material surrounding said member, an electric connection extending to the conducting member through the insulating material, and a metal surface-stud mounted in a depression in said member and having a contacting surface extending above the same.

17. In a roadway structure, the combination with a conducting-support, of insulating material surrounding said support, an in-

dependent metal disk or stud which is removably mounted within a depression in said conducting-support, and an electrical connection from the supply system through the insulating material to the support.

18. The combination with a conducting-support, of insulating material surrounding the same, an independent metal disk or stud which is removably mounted within a depression in said conducting-support, a metal casing for the insulating material, and an electrical connection to the support, which extends through the insulating material and metal casing, and is insulated from the latter.

19. The combination with a metal support formed with an upper depression, of a metal disk of less diameter than that of the depression and mounted therein, metal filling between the walls of the depression and the stud, and projections from the stud which substantially fit the depression and extend in the direction of motion of the cars, to prevent the car-collectors from loosening the stud.

20. The combination with a metal support formed with an upper depression, of a metal stud of less diameter than that of the depression and mounted therein, metal filling between the walls of the depression and the stud, projections from the stud which substantially fit the depression and extend in the direction of motion of the car, and holes in the projections, by which the stud can be removed from the depression of the support.

21. A stud for surface-contact electric railways, which consists of an independent disk formed with lateral projections.

22. In a roadway structure for surface-contact electric railways, the combination with a suitably-insulated conducting-support, means for connecting said support in circuit, and a removable surface-contact stud, the removal of which permits access to said connecting means.

23. In a roadway structure, the combination with a conducting member, of insulating material surrounding said member, an electrical connection extending to the conducting member, and a metal surface-contact disk or stud mounted within a depression in said member and having a central contacting surface extending above the same.

24. In a roadway structure, the combination with a conducting member having an electrical connection secured thereto, of a metal surface-contact disk removably mounted within a depression in said member and having its contacting-surface extending above the same.

25. In a roadway structure, the combination with a conducting member having an electrical connection secured thereto, of a metal surface-contact disk removably mounted in a depression in said member and having its upper surface sloping upwardly from the edges of the depression so as to form an upwardly-extending central contacting surface.

26. In a roadway structure, the combination with a conducting member having a shallow depression in its uppersurface, of a metal surface - contact disk removably mounted therein, the surface of the said disk sloping upwardly from the edges of the depression.

27. In a roadway structure, the combination with a conducting member having a shallow depression in its upper surface, of a metal

surface - contact disk removably mounted to therein, and a metal filling for securing said disk to the conducting member.

In witness whereof I have hereunto set my hand this 17th day of December, 1900.

WILLIAM B. POTTER.
